UNITED STATES PATENT OFFICE.

MOSES MOSLER, OF CINCINNATI, AND CARL BARTELS, OF HAMILTON, OHIO, ASSIGNEES
TO THE MOSLER SAFE COMPANY, OF NEW YORK, N. Y.

SAFE.

1,157,412.

Specification of Letters Patent. Patented Oct. 19, 1915.

Application filed June 12, 1915. Serial No. 33,685.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safes, of which the following is a specification.

10 This invention, pertaining to improvements in safes, will be readily understood from the following description taken in connection with the accompanying drawings in which:

15 Figure 1 is a front elevation of a safe exemplifying our invention: Fig. 2 a horizontal section of the same, in the plane of line *a* of Fig. 1: and Fig. 3 a horizontal section through a joint between shell-sections, in the plane of line *a* of Fig. 1.

In the drawings:—1, indicates a burglar-proof inner safe, illustrated as being circular in vertical cross-section and constructed, preferably, of unmachinable metal, 25 as cast manganese steel: 2, a circular door-jamb therein to receive a round door, this jamb being illustrated as having a threaded rear portion and a front portion formed with outwardly flaring taper: 3, a metallic shell inclosing the inner safe and formed in sections: 4, the rear section of the shell: 5, the front section of the shell: 6, the intermediate section of the shell joining the front and rear sections: 7, a cover-strip disposed around inside the shell and covering the joint between the front section and the intermediate section of the shell: 8, a similar cover-strip covering the joint between the rear and intermediate sections of the 30 shell: 9, a jamb-ring disposed around the doorway of the inner safe and projecting rigidly therefrom and having its front rigidly secured to the inner portion of the front section of the shell, this jamb-ring 35 having an outwardly flaring tapering circular jamb-opening: 10, a circular jamb formed in ring 9: 11, a round door having a rear portion threaded to fit the rear portion of the jamb of the inner safe and having a front portion fitting jamb-ring 9 and having an intermediate portion fitting the forward portion of the jamb of the inner safe: 12, the bearing and gear-casing disposed in front of the door and engaging a central journal on the door as is shown in

round door safes: 13, the usual crane-hinge having its heel pivoted to the general safe-body at one side of the door-opening, and having its free portion pivoted to the gear-casing 12, as is common in round door safes: 60 14, the dial of the usual combination lock: 15, the spindle mounted in the gear-casing, to be employed in rotating the door, as usual: 16, a wheeled pedestal of not unusual form for supporting the general safe construction: 17, fireproof filling disposed within the shell and around the inner safe and the jamb-ring 9: 18, the hinge-lugs for the crane-hinge, these lugs being formed with the jamb-ring and projecting out through 70 suitable openings in the front section of the shell: 19, an annular recess formed in the front section of the shell around the opening in jamb-ring 9: 20, the hinge-lugs for the crane-hinge, these lugs being formed with the jamb-ring and projecting out through 75 suitable openings in the front section of the shell: 19, an annular recess formed in the front section of the shell around the opening in jamb-ring 9: 21, a plate secured to the front of the front flange of ring 20: 22, fireproof filling disposed within ring 20 and filling the space 80 between plate 21 and the rear portion of door 11: 21, a plate secured to the front of the front flange of ring 20: 22, fireproof filling disposed within ring 20 and filling the space 85 between plate 21 and the rear portion of the door: and 23, the gear secured to the exterior surface of the door, within gear-casing 12, to serve in rotating the door, as usual in round door safes.

It is our preference that the shell be 90 formed in three sections, as illustrated, though a greater or less number of sections may be employed. Regardless of how many sections are employed in the formation of the shell one of the joints between sections 95 must be capable of being finally secured from the exterior of the shell. Thus in Fig. 2, illustrating three sections as being employed in the shell, cover-strip 7 may be permanently riveted in place before the shell 100 is finally closed, but one of the cover-strips, as at 8, may be riveted to one of the sections and secured to the contiguous section by means of screws going through the latter section and into the cover-strip. An appropriate ultimately closed opening is to be provided in the shell, preferably at its extreme bottom, through which the filling may be applied. Jamb-ring 9 may be secured to the inner safe by any appropriate means, 110

our preference being that, in case the inner safe is formed of manganese steel, it be provided with studs projecting from its front wall and engaging and riveted in front of the rear flange projecting outwardly from the jamb-ring. The front section of the shell may be secured to a front flange, projecting outwardly from the jamb-ring, by means of rivets or screws, but our preference is to employ screws passing through the inner portion of the front section of the shell and screwing into the front flange of the jamb-ring. Hinge-lugs 18 are carried by the jamb-ring, independent of the shell, thus permitting the door to be completely mounted and fitted in the absence of the shell. The recessing of the front of the shell, around the door-opening therethrough, permits the lessening of the forward projection of the gear-casing without any material impairment of the fireproof qualities of the safe. It is to be noted that the shell presents no exterior angles. This prevents injury in handling and gives to the general structure a peculiarly massive aspect, as much so as if the entire safe structure was a single burglar-proof safe of massive manganese steel construction.

The door may be provided with such locking arrangements as are usual in safes of round door type. Our preference is to have the door provided at its front with a combination lock, for day locking purposes, and at its rear with a time-lock for night security for the burglar-proof inner safe.

We claim:—

1. A safe comprising, a burglarproof inner safe-body provided in its front wall with a door-jamb extending inwardly from the extreme front of said burglar-proof safe-body and adapted to be closed by a door-member and thereby form a complete burglarproof safe, a jamb-ring rigidly secured to the extreme front of said inner safe concentric with said door-jamb, a shell surrounding said inner safe and secured to the front of the jamb-ring and having a door-opening concentric with the door-opening in the inner safe and jamb-ring, a door fitting 45 the jamb-ring, and filling material disposed within the shell around the inner safe and around the jamb-ring, combined substantially as set forth.

2. A safe comprising, a burglarproof inner safe-body provided in its front wall with a door-jamb extending inwardly from the extreme front of said burglarproof safe-body and adapted to be closed by a door-member and thereby form a complete burglarproof safe, a jamb-ring rigidly secured to the extreme front of said inner safe concentric with said door-jamb, a shell surrounding said inner safe and secured to the front of the jamb-ring and having a door-opening concentric with the door-opening in the in-

ner safe and jamb-ring, a door fitting the door-jamb of the inner safe and fitting the jamb-ring, and filling material disposed within the shell around the inner safe and around the jamb-ring, said shell being formed free of exterior angles, combined substantially as set forth. 70

3. A safe comprising, a burglarproof inner safe-body provided in its front wall with a door-jamb extending inwardly from the extreme front of said burglarproof safe-body and adapted to be closed by a door-member and thereby form a complete burglarproof safe, a jamb-ring rigidly secured to the extreme front of said inner safe concentric with said door-jamb, a shell surrounding said inner safe and secured to the front of the jamb-ring and having a door-opening concentric with the door-opening in the inner safe and jamb-ring, a door fitting the door-jamb of the inner safe and fitting the jamb-ring, and filling material disposed within the shell around the inner safe and around the jamb-ring, the extreme front of said shell projecting forwardly of the front of the jamb-ring and having an inner portion extending rearwardly into conjunction with the jamb-ring so as to form at the margin of the door-opening in the jamb-ring a recess rearward of the extreme front portion of the shell, combined substantially as set forth. 80

4. A safe comprising, a burglarproof inner safe-body provided in its front wall with a door-jamb extending inwardly from the extreme front of said burglarproof safe-body and adapted to be closed by a door-member and thereby form a complete burglarproof safe, a jamb-ring rigidly secured to the extreme front of said inner safe concentric with said door-jamb, a shell surrounding said inner safe and secured to the front of the jamb-ring and having a door-opening concentric with the door-opening in the inner safe and jamb-ring, a door fitting the door-jamb of the inner safe and fitting the jamb-ring, and filling material disposed within the shell around the inner safe and around the jamb-ring, hinge-lugs formed with said burglarproof inner safe and projecting outwardly through the front wall of the shell at one side of the jamb-ring, and means connecting said door and hinge-lugs and serving to cause the door to receive support from the inner safe through the medium of the hinge-lugs, combined substantially as set forth. 100

5. A safe comprising, a burglarproof inner safe-body provided in its front wall with a door-jamb extending inwardly from the extreme front of said burglarproof safe-body and adapted to be closed by a door-member and thereby form a complete burglarproof safe, a jamb-ring rigidly secured to the extreme front of said inner safe con- 110 120 125 130

centric with said door-jamb, a shell surrounding said inner safe and secured to the front of the jamb-ring and having a door-opening concentric with the door-opening in 5 the inner safe and jamb-ring, a door fitting the door-jamb of the inner safe and fitting the jamb-ring, filling material disposed within the shell around the inner safe and around the jamb-ring, hinge-lugs formed 10 with said burglarproof inner safe and projecting outwardly through the front wall of the shell at one side of the jamb-ring, and a crane-hinge having pivotal connection with the door and with said hinge-lugs and serving 15 to transmit the vertical strains due to the load of the door to the inner safe through the medium of said hinge-lugs, combined substantially as set forth.

6. A safe comprising, a door-jamb, a rear door-portion adapted to seat in and close 20 said jamb, an inwardly flanged ring having its rear flange secured to the front of said door-portion, a plate secured to the front of said ring, filling material disposed within said ring between said plate and the front 25 surface of said rear door-member, and a jamb-ring secured to the safe forward of said door-jamb and encircling said flanged ring, combined substantially as set forth.
